Filed Aug. 22, 1963, Ser. No. 303,792
10 Claims. (Cl. 233—15)

This invention relates to a flow directing centrifugal contacting apparatus which also provides a jet-type mixing action. More particularly, the invention is concerned with an apparatus for contacting two at least partially immiscible phases of different densities. The apparatus of the kind with which the present invention can be utilized has a rotor adapted for rotation about a horizontal axis, which rotor provides a cylindrical chamber extending radially outward from the axis. The radially innermost and outermost portions of this chamber provide respectively light and heavy phase clarifying zones and the intermediate portion of the chamber provides a contacting zone. Devices of the kind with which this invention is concerned are described in United States Patents 2,758,783 and 2,758,784.

As illustrated by the patents just cited, it has been the practice to employ perforated rings within the contacting section of the rotor. The rings are usually concentrically arranged in radially spaced relation so that the phases must pass through the ring perforations in moving inwardly and outwardly through the annular passageways provided between the rings. The predominant flow within the contacting section is therefore countercurrent with the heavy phase moving outwardly through the perforations and the light phase moving inwardly through the same perforations. With this arrangement, the phases distribute themselves relatively uniformly throughout the contacting section of the rotor, but the stage efficiency achieved is far below that which should be theoretically possible. No particular flow direction is imposed on the phases within the annular passageways.

Some attempts have heretofore been made to impose a more definite flow pattern on the phases within the contacting section of the rotor. For example, prior Patent 2,758,783 describes contacting rings having offset sectional perforated areas. Such a design is of value in preventing a tendency of either or both phases to channel through the contacting section without being repeatedly mixed and separated.

In prior Patent 2,840,301 a centrifugal countercurrent contacting apparatus is described employing contacting rings which are provided with axially and circumferentially distributed perforations, and also with nozzle-equipped orifices or larger cross-sectional area than the perforations. With this construction, depending on the radial direction in which the nozzles extend, the light or heavy phase, as the case may be, tends to flow predominantly through the orifices, while the other phase flows predominantly through the ring perforations. In operation, as with other ring-equipped centrifugal contacting devices, the mixing and separation of the phases occurs within the ring passageways, but the flow of the phases is not controlled to the extent that there are definite mixing and separating areas within the passageways.

Redlich Patent 2,169,280 describes a centrifugal contactor and method of contacting wherein an effort is made to hold one of the phases in quiet zones of substantial radial depth along the inside or outside walls of the perforated rings. According to the disclosure of this patent, the other phase is made to flow axially across these "quiet" zones, the axially flowing phase is brought into contact with dispersed droplets of the phase which passes from the quiet zones through the ring perforations into the

flowing stream. In this type of design therefore it is proposed to provide a mixing zone adjacent one wall of the rings and a clarification or separating zone against the other wall of the rings. In other words, the interring mixing and clarification areas extend across the full axial length of the rotor. In practice, however, the use of close band spacing and the existence of rotational swirl imposed on the phases by the high rotational speed of the rotor, would tend to make it extremely difficult to establish and maintain such a flow pattern.

It is therefore a general object of this invention to provide a centrifugal contacting apparatus and more particularly to provide flow directing means within the contacting section of the rotor which imposes a substantial degree of control on the flow of both of the phases through the contacting zone. More specifically, it is an object to provide an apparatus of the character described which establishes and maintains definite mixing and contacting areas within the inter-ring passageways. Still another object is to achieve the indicated results by employing contacting rings or elements of special design which provide sequential mixing and separating areas between the contacting elements even though the contacting elements or rings are closely spaced when the apparatus is operated at high rotational speeds. More specifically, it is an object of this invention to employ means with radially spaced contacting rings which provide a flow pattern within each of the annular passageways between the rings whereby the phases are intermixed in one area, passed cocurrently to another area, and separated as they pass respectively inwardly or outwardly to the next adjacent annular passageway. Still another object is to provide in combination with such apparatus, means for achieving a substantially jet-type mixing of the phases as they enter the annular passageways. Further objects and advantages will be indicated in the following detailed specification.

The invention is illustrated in several embodiments thereof in the accompanying drawing, in which—

40 FIGURE 1 is a side sectional view of a portion of a centrifugal rotor embodying features of the present invention;

45 FIGURE 2 is a fragmentary sectional end view of two of the contacting rings of the apparatus of FIG. 1, taken on line 2—2 of that figure;

FIGURE 3 is a side sectional view of a portion of a centrifugal rotor embodying a modified form of the present invention;

FIGURE 4 is a fragmentary sectional view of the interior of the rotor of FIG. 3, taken on line 4—4 thereof, showing particularly the heavy phase removal means;

FIGURE 5 is a fragmentary sectional view of one of the center portions of two adjacent contacting elements in the rotor of FIG. 3.

55 Looking first at FIG. 1 of the drawings, there is shown a portion of a centrifugal contacting apparatus having a rotor 10 adapted for rotation about a horizontally-extending shaft 11. Rotor 10 is formed from side plates 10a and 10b and an outer cylindrical plate 10c. The general construction and operation of such centrifugal rotors is described in prior Patents 2,758,783 and 3,053,440. As is well-known in the art, means is provided for driving the shaft 11 at controlled rotational speed, the shaft being mounted on suitable bearings, and means is also provided for introducing and removing liquids from the passages within the shaft.

As can be seen by the further consideration of FIG. 1, rotor 10 provides a cylindrical chamber 12 therein which extends radially outward from shaft 11. The shaft includes an internal passage 13 for supplying the light phase to the rotor chamber through radially extending tubes 14. Shaft 11 also provides a passage 15 for supplying the

heavier phase through radially extending tubes 16. The lighter phase is removed from a position adjacent shaft 11 through lateral passages 17 which connect with shaft passage 18. The passage for removal of the heavy phase is provided by spill-over disc 19 and end wall 10a, the passage being designated by the number 20, and this passage connecting with shaft passage 21. It will be noted that the light phase is introduced to chamber 12 at a position considerably further out in the rotor chamber than the position at which the heavy phase is introduced, the region between the points of introduction of the light and heavy phases comprising the principal extracting flow area or contacting zone. Also, it will be noted that the heavy phase is removed from a position substantially further out than the point of introduction of the light phase, the region therebetween comprising the principal heavy phase clarification section. Similarly, the light phase is removed from a position considerably closer to the shaft than the point of introduction of the heavy phase, the region therebetween comprising the principal clarification section for the light phase. Within the contacting section of rotor 12 there is provided a group of rings disposed in radially spaced relation, which provide a plurality of generally annular axially-extending passageways therebetween. Preferably, as shown, these passageways are circumferentially and axially open and unobstructed to liquid flow. In the illustration given in FIG. 1, the contacting rings include alternately positioned rings 22 and 23, the rings being substantially identical in construction except for the respective left and right hand reversal within the rotor chamber. FIG. 1 illustrates a preferred embodiment of the present invention wherein the rings 22 and 23 have a frusto-conical shape. As will be noted, rings 22 and 23 provide walls which are inclined at a small acute angle with respect to the horizontal on a vertical plane or section including the axis of the rotor, such as the section of FIG. 1. In accordance with the present invention, walls 22 and 23 are arranged in an alternating pattern within the contacting section of the rotor. For example, in the illustration given, the rings 22 provide walls which converge toward the right hand end or side of the rotor, while the rings 23 provide walls which converge toward the left hand side of the rotor. It is preferred to have the rings 22 and 23 extend entirely across the length of the rotor space, as shown.

In accordance with the present invention each of the contacting rings, such as the rings 22 and 23, are provided with at least two perforated plate sections for radial phase flow. The rings 22 have perforated plate sections 22a and 22b, while the rings 23 have corresponding perforated plate sections 23a and 23b. These perforated sections are respectively separated by relatively imperforate areas of the rings, which in the illustration given are designated respectively by the numbers 22c and 23c. Plate sections 22a and 23a are for the flow of the heavier phase to the next outer one of the annular passageways. Plate sections 22b and 23b are for the flow of the lighter phase to the next inner one of the passageways. As will be noted, each of the plate sections 22a, 22b, 23a and 23b are provided with a plurality of small perforations which extend across the axial width of the sections. It will be understood that the perforations in these sections also extend circumferentially around the rings. In embodiments like that of FIG. 1, it is preferred to have the perforated plate sections located in the axially outer portions of the rings adjacent the sides 10a and 10b.

In accordance with the present invention, plate sections 22a and 22b are positioned respectively in radially opposed relation to plate sections 23b and 23a for adjacent rings. This arrangement provides at least two pairs of opposed plate sections for each of the annular passageways between the rings. As will be noted, the imperforate areas 22c and 23c are also in radially opposed relation. In the operation of the device of the present invention, one of the pairs of plate sections serves as phase entrance ports for the passageways and the other pair

5 serves as phase exit ports. It will be understood that a particular plate section on one side will serve as an entrance port for the annular passageway on that side, while serving as an exit port for the annular passageway on the other side. For example, as shown in FIG. 1, the plate sections 22b and 23a serve as entrance ports for the outermost annular passageway of the contacting section designated by the letter a, while the plate sections 23a and 22b serve as exit ports for the next innermost annular passageway designated by the letter b. Similarly, the exit ports 10 for the passageway a are provided by the plate sections 22a and 23b, and the entrance ports for the passageway b are provided by the plate sections 23b and 22a.

15 In achieving the benefits of the present invention, such as directed phase flow and jet-type mixing action, it is important that the perforated plate sections within each of the rings be located at different radial distances from the axis of the rotor. For example, in the embodiment of FIG. 1 the plate sections 22a and 23a are located at greater radial distances from the axis of the rotor than their respective sections 22b and 23b. In other words, there should be a definite change in radial flow position or level between the perforated plate sections of each ring. The relationship can also be stated in terms of the 20 radial spacing of the pairs of plate sections for each annular passageway. More specifically, the plate sections providing the entrance ports should be more closely spaced than the plate sections providing the exit ports. With this construction, the phases are forced through 25 the entrance ports with each of the phases being broken-up into fine streams or jets which meet head-on within the confined space between the entrance ports, thereby achieving thorough intermixing and mutual dispersion of the phases. The phases are then passed co-currently through 30 the portions of the passageways between the imperforate areas, such as the areas 22c and 23c, and separated in the portions of the passageways between the exit ports. With the frusto-conical rings of the embodiment of FIG. 1, the separation and clarification of the phases is promoted by 35 the movement of the phases along the inclined walls into an enlarging portion of the rotor passageway.

40 In FIG. 1, the flow of the phases through the rotor and the contacting section thereof is indicated by the flow arrows, some of which are further identified with a H or an L enclosed within a circle, which indicates respectively the heavy or the light phase. In operating devices 45 constructed in accordance with the present invention, it is preferred that the perforated plate sections which function as exit ports from a particular passageway should have a layer of the separated phase maintained thereon so that the perforations pass only the desired phase to the next annular passageway while largely excluding any flow in the opposite direction through the same perforations of the opposing phase. For example, as shown in FIG. 1, the heavy phase enters through the tube 16 and flows along the inner surface of the innermost ring 23 toward the plate section 23a. As indicated in FIG. 1, a layer of the heavy phase H is maintained on the inside 50 surface of the plate section 23a. Similarly, the light phase is introduced through the tubes 14 outside of the outermost ring 22, passing along the outside surface of the ring to form a layer L on the outside surface of plate section 22b. Within the annular ring passageways, such as the passageway a, layers of the heavy phase H and the light phase L are maintained over the inside surfaces of 55 the exit plate sections. It will be understood that the drawing shows these phase layers somewhat diagrammatically, and that the exact boundaries of the phase layers need not be as illustrated.

60 A modified embodiment of the present invention is illustrated in FIGS. 3 to 5. Looking first at FIG. 3, there is shown a centrifugal countercurrent contacting apparatus having a rotor 100 adapted for rotation about a horizontal axis, the rotor being rigidly mounted on a horizontally-extending shaft 101. Rotor 100 is formed from side plates 100a and 100b and an outer cylindrical plate 100c.

The general construction and operation of rotor 100 is similar to the rotor 10 of FIG. 1.

Rotor 100 provides a cylindrical chamber 102 which extends radially outwardly from shaft 101. The shaft includes an internal passage 103 for supplying the light phase to the rotor chamber through radially extending tubes 104. Shaft 101 also provides a passage 105 for supplying the heavier phase through radially extending tubes 106. The lighter phase is removed from a position adjacent shaft 101 through lateral passages 107 which connect with shaft passage 108. The heavy phase is removed through a tubular return 120 which communicates with a shaft passage 121. The inlets to tubular return 120 are designed as 120a.

Within the contacting section of rotor 12 there is provided a group of rings disposed in radially spaced relation. In the illustration given, the contacting rings include alternately positioned rings 122 and 123, the rings being formed of two frusto-conical members, which are united at their centers by welding, as indicated more clearly in FIG. 5. As will be noted, the walls of adjacent rings alternate with respect to their convergence and divergence toward the center and sides of the rotor. This arrangement adapts the basic construction of the contacting elements of FIG. 1 for extended rotors, that is, for rotors which have a relatively long axial extent. For example, this design would be well adapted for rotors having axial widths of from 40 to 60 inches. As with the embodiment of FIG. 1, the walls provided by rings 122 and 123, have portions which are inclined at acute angles with respect to the horizontal at the inner sections of the wall portions with a vertical plane through the axis of the rotor.

The rings 122 and 123 respectively provide three perforated plate sections for radial phase flow, these sections in the rings 122 being designated as 122a, 122c, and 122e, and the corresponding sections in the rings 123 being designated as 123a, 123c, and 123e. As with the embodiment of FIG. 1, the perforated plate sections are separated by relatively imperforate areas of the rings, which in the illustration given are designated by the numbers 122b and 122d for the rings 122, and by the numbers 123b and 123d for the rings 123. The phase flow through the perforated sections, and through the passages between the rings is indicated by arrows in FIG. 3. Speaking generally, where the perforated plate sections are relatively close together, the phases flow towards each other and are intermixed, while where the perforated plate sections are relatively far apart, the phases flow away from each other as they are separated. As will be noted, the intermixing of the phases and the separation of the phases alternately occurs at the center of the rotor and adjacent the sides thereof. For example, with respect to the outermost ring 122 and the next innermost ring 123, the phases are intermixed adjacent the sides of the rotor, flow inwardly toward the center, and are separated, passing outwardly and inwardly respectively through the plate sections 122c and 123c. With respect to the space provided between the next inward ring 122 and the outermost ring 123, the intermixing of the phases occurs at the center, and the phases then flow outwardly concurrently in both directions, and are separated adjacent the perforated sections 123a, 122a, and 123e, and 122e. This alternating flow pattern is then repeated sequentially as the phases flow inwardly and outwardly through the contacting section of the rotor.

The embodiment of FIG. 3, also includes perforated rings in the light and heavy clarifying zones of the rotor. In the illustration given, the heavy phase clarifying zone includes perforated rings 125 and a partially perforated ring 125'. Similarly, the light phase clarifying zone includes perforated rings 124 and a partially perforated ring 124'. The construction of the partially perforated ring 125' is shown more clearly in FIG. 4. The ring includes an imperforate area 125a' immediately surrounding the pickup inlets 128a for the removal of the heavy phase

through the tubular return 120. This construction provides for more uniform pickup of the heavy phase across the full width of the rotor, and prevents any tendency of the heavy phase to channel through the central portion of the heavy phase clarifying zone. The use of a specially designed pickup ring, such as the ring 125' immediately radially inward of the heavy phase outlets is especially desirable in relatively wide rotors, that is, rotors which have an axial extent of 40 inches or more. However, it can also be advantageously used in rotors of narrower width. It will be understood that the construction of the ring 124' is similar to that of the ring 125', and that the ring 124' provides an imperforate area 124a' in opposed relation to the light phase outlets 107.

Preferably, suitable elements, such as perforated rings, are included in the light and heavy clarifying zones of the rotor. For example, as illustrated in FIG. 1, the light phase clarification zone is provided with a group of perforated concentric rings 24. The primary purpose of the rings 24 is to promote clarification of the light phase, and usually at least three such rings will be employed. In the outer portion of rotor chamber 12 there is provided another group of radially spaced concentric rings 25. Rings 25 are similar to rings 24 in that they are provided with axially and circumferentially distributed perforations. Rings 25 are intended primarily to promote clarification of the heavy phase. Usually at least two such rings will be employed, although in certain cases the number of heavy phase clarification rings can be further reduced or eliminated altogether. Other types of elements in the clarifying zones can also be employed, such as the axially-spaced radially-extending disc described in Patent 3,053,440.

It will be understood that the present invention does not require the use of any particular number of rings within the contacting section of the rotor. However, usually at least eight rings, or four pairs of rings, will be employed. The preferred number of rings in the contacting section, of course, will depend on the diameter of the rotor, which can range from 10 to 60 inches in diameter, but will usually be from 20 to 50 inches in diameter. The permissible rotational speed will vary inversely with the rotor diameter. For example, speeds up to 5,000 r.p.m. can be used with a 12 inch rotor diameter, while speeds as low as 1,200 r.p.m. may be preferred for a 60 inch rotor diameter. With rotors having diameters ranging from 20 to 50 inches, the rotational speeds will usually range from 4,000 to 1,600 r.p.m.

The perforations in the opposed plate sections of the contacting rings can vary in size according to the particular phase systems being contacted, the desired flow rates, etc. The pressure drop across the ring perforations should be sufficient to maintain substantially uni-directional flow, and thereby avoid any undue channeling of the opposite phase. Usually perforation diameters of from $\frac{1}{16}$ to $\frac{1}{4}$ inch can be used. The radial distance or "clearance" between the rings in the contacting section can also vary over a considerable range. Usually, however, the maximum clearance between the rings will not be greater than 2 inches, while the minimum clearance will not be less than $\frac{1}{4}$ inch. With the embodiment of FIG. 1, the ring clearance will vary from the entrance port end to the exit port end of the passageways. Usually, the maximum clearance at the exit port end of the passageways will not be greater than 2 inches, and the minimum clearance at the entrance end of the passageways will not be less than 0.2 inch.

With respect to each individual ring, the two different flow port providing sections should have radial positions differing by at least 0.2 inch and preferably by at least 0.4 inch. With the embodiment of FIG. 1, these radial distances would apply to the outer ends of the rings, while with the embodiment of FIG. 3 the radial distances would apply to the perforated plate sections, such as the sections 100a and 100b. The difference in the radial positions

of the perforated plate sections can be increased over the figures given, but after a certain point is reached the increase in stage efficiency within each annular passageway is offset by the reduction in the total number of passageways which can be included within a given diameter rotor. Usually, the difference in radial position of the perforated plate sections for each ring will not be greater than 1 inch.

With devices of the character described herein, a pressure differential is maintained between the light phase in and the light phase out. More specifically, the light phase is pumped to the rotor under a substantial pressure, say 50 to 200 p.s.i., while the light liquid out is removed from the rotor at a lower pressure of say, 40 to 180 p.s.i. A back pressure regulator or a throttling valve is employed to maintain the pressure on the light liquid out. The heavy liquid is also pumped into the rotor under substantial pressure, which usually approximates the back pressure on the light liquid out. While back pressure can be maintained on the heavy liquid out, usually the heavy liquid is discharged to the atmosphere with no back pressure being maintained. The principal interfacial boundary between the light and heavy phases within the rotor can be controlled by regulating the light liquid out back pressure in relation to the light liquid in pressure. Usually, the useful range of variation will be where the light liquid out pressure is from 30 to 90% of the light liquid in pressure. When the light liquid out pressure is low relative to the light liquid in pressure, the principal interface will approach the rotor shaft. When the light liquid out pressure is relatively high compared with the light liquid in pressure, the interfacial boundary will move toward the outer position of the rotor. However, one of the advantages of rotors constructed in accordance with the present invention is that the rotor will operate satisfactorily with the principal interface in varying positions ranging from a position within the heavy liquid clarifying section through positions within the contacting section, to positions within the light liquid clarifying sections. It will be understood, however, that the back pressure on the light liquid out should not be so low that the rotor floods with the heavy phase, nor should the back pressure be so great that the rotor floods with the light phase.

The contacting apparatus of this invention can be employed in a variety of applications. For example, the apparatus can be utilized for the extraction of hydrogen peroxide from an oxidized solution of hydroquinone compound into water. It can also be used for the phenol or furfural extraction of petroleum oils, such as lubricating oils, and for caustic treatment of gasoline.

While in the foregoing specification this invention has been described in relation to a number of specific embodiments thereof and many details have been set forth for purpose of illustration, it will be apparent to those skilled in the art that the invention is susceptible to additional embodiments, and that many of the details described herein can be varied considerably without departing from the basic principles of the invention.

We claim:

1. In an apparatus for centrifugal contacting of two at least partially immiscible liquid phases of different densities, said apparatus being of the kind having a rotor adapted for rotation about a horizontal axis and providing a cylindrical chamber therein extending radially outward from said axis, the radially innermost and outermost portions of said chamber providing respectively light and heavy phase clarifying zones and the intermediate portion of said chamber providing a countercurrent contacting zone,

a group of rings disposed in radially spaced-apart relation within said contacting zone to provide a plurality of annular axially-extending passageways therebetween,

each of said rings being provided with at least two perforated plate sections for radial phase flow with

a relatively imperforate area of said ring extending therebetween,

one of said plate sections of each ring being for the flow of the heavier phase to the next outer one of said passageways,

the other of said plate sections being for the flow of the lighter phase to the next inner one of said passageways,

said one plate sections being positioned in radially-opposed relation to said other plate sections for adjacent rings to provide at least two pairs of opposed plate sections for each of said passageways, the imperforate areas of adjacent rings also being in radially-opposed relation,

one of said pairs of plate sections serving as phase entrance ports for each of said passageways and the other pair serving as phase exit ports,

within each of said rings said one plate section being located at a greater radial distance from said axis than said other plate section and the said imperforate section which extends therebetween being inclined at an acute angle with respect to the horizontal at the intersection of the said imperforate section with an imaginary vertical plane through the axis of said rotor,

whereby said phases are forced through the pairs of plate sections serving as said entrance ports for thorough intermixing in the portions of said passageways between said entrance ports, passed co-currently through the portions of the passageways between said imperforate areas, and separated in the portions of the passageways between said exit ports.

2. The apparatus combination of claim 1 wherein said perforated plate sections are axially spaced-apart and extend circumferentially around said rings.

3. The apparatus combination of claim 2 wherein said rings are each provided with two of said perforated plate sections with one of said imperforate areas extending therebetween.

4. The apparatus combination of claim 2 wherein said rings are each provided with three of said perforated plate sections with said imperforate areas extending therebetween.

5. The apparatus combination of claim 1 wherein at least two of said perforated plate sections are located in the axially outer portions of said rings and extend circumferentially therearound.

6. The apparatus combination of claim 1 wherein each of said rings has a frusto-conical shape extending across said rotor, the walls of adjacent rings alternately converging towards opposite sides of said rotor.

7. The apparatus of claim 1 wherein each of said rings is formed from a pair of frusto-conical members, the walls of adjacent rings alternating with respect to their convergence and divergence toward the center and sides of said rotor.

8. In an apparatus for centrifugal contacting of two at least partially immiscible liquid phases of different densities, said apparatus being of the kind having a rotor adapted for rotation about a horizontal axis and providing a cylindrical chamber therein extending radially outward from said axis, the radially innermost and outermost portions of said chamber providing respectively light and heavy phase clarifying zones and the intermediate portion of said chamber providing a countercurrent contacting zone,

a group of rings disposed in radially spaced-apart relation within said contacting zone to provide a plurality of annular axially-extending passageways therebetween, said passageways being circumferentially and axially open and unobstructed to liquid flow, said rings being formed of at least one frusto-conical member, and providing wall portions inclined at an acute angle with respect to the horizontal at the in-

tersections of said wall portions with a vertical plane through the axis of said rotor, each of said rings being provided with at least two perforated sections arranged in axially-spaced relation with a relatively imperforate area of the ring extending therebetween, 5 one of said perforated sections being for the flow of the heavier phase to the next outer one of said passageways, one of said perforated sections being for the flow 10 of the lighter phase to the next inner one of said passageways, the other of said perforated sections being positioned in radially opposed relation for adjacent rings to provide two pairs of opposed perforated sections for each of 15 said passageways, the imperforate areas of adjacent rings also being in radially-opposed relation, one of said pairs of sections serving as phase entrance 20 ports for each of said passageways and the other pair serving as phase exit ports, said plate sections serving as phase entrance ports being radially closer together than the sections serving as 25 said exit ports.

9. The apparatus combination of claim 8 wherein each of said rings is formed from a pair of frusto-conical members, the walls of adjacent rings alternating with respect to their convergence and divergence toward the center and sides of said rotor. 30

10. In an apparatus for centrifugal contacting of two at least partially immiscible liquid phases of different densities, said apparatus being of the kind having a rotor adapted for rotation about a horizontal axis and providing a cylindrical chamber therein extending radially outward from said axis, the radially innermost and outermost portions of said chamber providing respectively light and heavy phase clarifying zones and the intermediate portion 35

of said chamber providing a countercurrent contacting zone, a group of rings disposed in radially spaced-apart relation within said contacting zone to provide a plurality of annular axially-extending passageways therebetween, said passageways being circumferentially and axially open and unobstructed to liquid flow, said rings having a frusto-conical shape and providing walls inclined at an acute angle with respect to the horizontal at the intersections of said walls with a vertical plane through the axis of said rotor, the walls of adjacent rings alternately converging towards opposite sides of said rotor to provide passages therebetween which are relatively narrow at one end and enlarged toward their opposite end in an alternating pattern from one ring passageway to the next adjacent ring passageway, said rings adjacent their converging end portions providing phase entrance port means respectively for the light phase and the heavy phase so that said phases are introduced into the narrow end portion of said passageways and pass cocurrently toward the enlarged end portions thereof, and phase exit port means provided adjacent the diverging end portions of said rings respectively for the light phase and the heavy phase so that said phases may separate within the enlarged end portions of said passageways and flow therefrom into the restricted end portions of the next adjacent passageways.
